AIRWAY TRAFFIC CONTROL SYSTEM

Oscar S. Field and Sedgwick N. Wight, Rochester,
N. Y., assignors to General Railway Signal
Company, Rochester, N. Y.

Application November 30, 1944, Serial No. 565,858

10 Claims. (Cl. 343—11)

1 This invention relates to blind landing and blind route delineation apparatus for aiding pilots of airplanes in landing and in route flying during poor visibility and is an improvement over the prior application of Field, Wight, and Saint, Ser. No. 517,814, filed January 11, 1944, now Patent No. 2,463,094, issued March 1, 1949, and over our prior application, Ser. No. 548,660, filed August 9, 1944, now Patent No. 2,463,095, issued March 1, 1949.

As set forth in the above mentioned prior applications it is desirable for safe flying and landing to have pictorially displayed on a screen before the pilot the locations of ground located radio radiators. This requires suitable space energy transmission which will penetrate fog, such as radio energy. In order to display a plurality of such radio radiators at the same time and on the screen of the same cathode-ray tube it is necessary to scan the field of view ahead of the airplane. In accordance with the present invention the swinging of radio beams or focused antennas are to be avoided and the scanning is to be accomplished by triangulation methods involving the difference in radio transmission time over two related paths from a field location to two points on an airplane to indicate the direction of the ground located radio radiator in, say, a horizontal plane and horizontally on the screen, and to employ the time of a radio echo or time of return of a radio triggered impulse to indicate, say, vertically on the screen the distance to such radio reflector or re-radiator.

More specifically, it is proposed to use comparatively short wave length radio energy and to space two receiving antennas on the airplane at right angle and on opposite sides of the same point of the flight axis that the maximum difference in distance from these antennas from a ground located radio radiator located anywhere ahead of the airplane cannot be more than a full wave length (one-half plus wave length and one-half minus wave length), so that this difference in distance can be detected by the phase displacement between two received radio currents. In order to measure the distance to such ground located radio radiator it is proposed to render ground located retransmitting apparatus active intermittently and in response to triggering radio energies transmitted from the airplane, to start a sweep of an electron beam in a cathode-ray tube when the triggering radio radiation leaves the airplane and to plot a fluorescent spot by such beam when

the radio energy has been returned to the two antennas and then only when the electron beam scans the screen in a corresponding direction.

Another object of the present invention resides in the provision of means for causing an electron beam to scan a fluorescent screen of a cathode-ray tube radially, such radial scanning preferably extending only through an angle of 180° about a center located at the lower middle part of the screen.

In accordance with another form of the invention it is proposed to ascertain the difference in length of two radio beams directly and irrespective of the frequency used and irrespective of phase relationship.

Other objects, purposes and characteristic features of the invention will be pointed out as the description progresses and will in part be obvious from the accompanying drawing in which:

Fig. 1A illustrates conventionally one embodiment of the invention in which maximum phase displacement between received radio currents is one cycle;

Fig. 1B illustrates the apparatus for one ground location;

Fig. 2 illustrates how the form of the invention of Fig. 1 may be modified, if the frequency of the radio currents is reduced fifty per cent without any change in the spacing of the receiving antennas;

Fig. 3 shows how the speed of the phase shifting portion of the system shown in Fig. 1A may be doubled if two-phase shifting units instead of one are employed;

Fig. 4 modifies Fig. 3 in the same manner as Fig. 2 modifies Fig. 1A;

Fig. 5 illustrates graphically a uniform saw-tooth current, how this saw-tooth current may be modulated into two saw-tooth modulated currents displaced 90° in phase and how these currents may be commutated or pole changed to produce the necessary currents to cause semi-circular radial scanning of the fluorescent screen;

Fig. 6 shows graphically how phase displacements between 0 and 180° phase displacement may be compared by pole changing one of these circuits each time the phase shifter has shifted through an angle of 180°;

Fig. 7 illustrates a phase shifter of the condenser type which may be substituted for the inductive type phase shifter illustrated in Fig. 1A and if this is done the system will function

in exactly the same manner as does the system of Fig. 1;

Fig. 8 illustrates how phase shifting may be accomplished by adding to or subtracting from the length of an electron path; and

Fig. 9 illustrates another form of the invention in which the difference in arrival time of two radio currents, irrespective of their wave length, is measured by apparatus similar to that disclosed in Fig. 8.

Figs. 1A and 1B structure.—Referring to Fig. 1A of the drawings, the reference character AP designates, by conventionally showing the wings of an airplane, an airplane on the body of which there is located a transmitting antenna TA whereas each of the wings supports a receiving antenna which receiving antennas have been designated RA1 and RA2. These receiving antennas are preferably supported equal distances from the center line of the airplane and on opposite sides of the same point of this center line. In the forms of invention illustrated in Figs. 1, 3 and 8 these receiving antennas RA1 and RA2 are separated a distance of one-half wave length of the radio energy transmitted by transmitting antenna TA and received by receiving antennas RA1 and RA2. In the form of inventions illustrated in Figs. 2 and 4 the frequency of the radio energy employed is presumably half as high so that the wave length of such radio energy is twice that of the former and so that the receiving antennas RA1 and RA2 even though physically spaced the same distance are separated a distance of one-fourth wave length in the form of invention illustrated in Figs. 2 and 4.

By referring to Fig. 1A it will be readily seen that if energy is transmitted to the two receiving antennas RA1 and RA2 from the extreme left of the flight line (90° to the left) that this radio energy will be received by antenna RA1 one-half cycle before it will be received by antenna RA2 but that if energy is transmitted from the lower part of the drawing, namely, from the extreme right (90° to the right) of the line of flight that this radio energy will reach the antenna RA2 one-half cycle before it will reach the antenna RA1. In other words, the maximum phase displacement that can exist between radio energies received from a ground location ahead of the airplane by the two antennas RA1 and RA2 is one whole cycle or 360°. That is, the energy received by one antenna may lag as much as 180° behind the energy received by the other antenna and may sometimes lead as much as 180° the energy received by the other antenna so that the maximum phase shift between these two energies that can ever exist is one cycle or 360°.

It is deemed desirable to now briefly discuss the apparatus located at a particular ground location. This apparatus has been illustrated in Fig. 1B and includes a ground receiving antenna GRA delivering its output energy to a ground receiver GR and which in turn controls or triggers the ground transmitter GT. This apparatus also includes a ground transmitting antenna GTA which is activated by the ground transmitter GT. It will be observed that the ground receiver GR is connected to the ground transmitter GT so that this ground transmitter GT is activated and repeats the signal received by the ground receiver GR. It is thus seen that if a pulse of radio energy is transmitted by the airplane transmitting antenna TA to the entire surrounding area in advance of the airplane, the transmitting antenna TA spreading its energy out through substantially an

angle of 180°, that this energy will cause each of one or more of the ground transmitters GT to be rendered active and cause the transmission of a radio impulse back toward the airplane from each of such ground stations through the medium of the ground transmitting antenna GTA and it will also be observed that the phase relationship between the energies picked up by the two airplane carried receiving antennas RA1 and RA2 from any particular ground station will be displaced in phase dependent upon whether the ground located transmitting antenna is located directly ahead of the airplane, is located toward the right or toward the left of the center line of the airplane. Although this ground located apparatus has been shown in block form it is readily understood that this apparatus may comprise a simple radio energy repeater including electron tubes which have their filaments continuously heated so that the transmitting antenna GTA will relay or retransmit an increased quantity of the same character of radio energy that is received by the associated ground receiving antenna GRA.

Referring again to Fig. 1A in accordance with the specific form of the invention illustrated therein the airplane carried transmitter TR does not transmit radio energy continuously through the medium of its antenna TA but transmits intermittent pulses of radio energy each pulse of which consists of a large number of cycles of high frequency radio energy of a wave length commensurate with the spacing of the receiving antennas RA1 and RA2. If these receiving antennas RA1 and RA2 are, for instance, spaced 10 meters apart then each wave length will be 20 meters long and the frequency of the radio energy will be 15 mc. (megacycles). The radio transmitter TR conventionally shown in Fig. 1A includes a suitable electronic tube oscillator which is constructed to generate alternating current of this frequency of, say, 15 mc. which transmitter is, however, inactive unless rendered active by the pulse generator IG. This pulse generator IG performs two functions. It causes intermittent transmission of radio energy through the medium of the transmitter TR and the transmitting antenna TA and also causes the saw-tooth generator STG to be agitated once for each saw-tooth generated and each impulse transmitted, so that the saw-teeth of energy generated by the saw-tooth generator STG are in synchronism with the pulses of radio energy transmitted by the transmitting antenna TA, there being a short radio pulse transmitted by the transmitting antenna TA at the beginning of each saw-tooth wave energy generated by the saw-tooth generator STG. It may be pointed out at this time that this saw-tooth energy is used to deflect an electron beam in a cathode-ray tube so that the distance a ground location is from an airplane may be plotted on the screen of such cathode-ray tube, all as more fully pointed out hereinafter. It is considered desirable to now describe the cathode-ray tube together with means for sweeping the electron beam thereof by energy derived from the saw-tooth generator STG.

The cathode-ray tube K is of the usual construction but instead of having been shown of usual conical configuration it has been illustrated as of pyramidal construction. This cathode-ray tube includes a fluorescent screen S of well-known construction upon which impinges an electron beam EB which beam is emitted by the electron gun including a cathode Ca energized through the medium of a filament energized from

a filament battery FA, a grid G, a first anode A1 and a second anode A2. The first anode also serves as a focusing device to focus the electrons into a comparatively narrow beam as by adjusting the potential applied thereto from the direct current source AB as through the medium of the potentiometer 34. It also includes sweep plates 10 and 11 for causing a horizontal component of sweeping of the electron beam EB and includes sweep plates 12 and 13 for producing a vertical component of sweep. These sweep plates 10-11 and 12-13 are so energized by the saw-tooth energy that the electron beam EB, which is biased by the battery KB to the position O on the screen, is scanned radially successively through an angle of 180° after which such scanning performance is repeated.

To obtain such radial scanning suitable saw-tooth energy conversion apparatus is necessary and this apparatus has been illustrated near the top in Fig. 1A and includes a single stationary ring coil 20 and two other ring coils 21 and 22 mounted on a shaft 23 in such manner that the axis of these two coils 21 and 22 are at right angles to each other and are also at right angle to the axis of rotation. This shaft 23 is driven by a motor M operating at a speed dependent upon the number of scans per second of scanning of the cathode-ray screen S that are desired. If it is desired to scan this screen 16 times per second the shaft 23 is rotated at a speed of 8 revolutions per second, there being two scans per revolution, or 480 R. P. M. It will be noted that two-segment commutators are provided. The commutator 25-26 includes commutator segments 25 and 26 suitably supported by the shaft 23 and which segments are connected to the lead-out wires of the rotating coil 21 through the medium of wires a and b. The segments 27 and 28 of the commutator 27-28 are connected to the other rotating coil 22 through the medium of wires c and d as illustrated. The commutator 25-26 has associated therewith stationary brushes 35 and 36 whereas the commutator 27-28 has associated therewith stationary brushes 37 and 38. The brushes 35 and 36 are connected to the vertical sweep plates 12 and 13 through wires 32 and 33, whereas the brushes 37 and 38 are connected to the horizontal sweep plates 10 and 11 through the medium of wires 30 and 31.

Let us now for a moment refer to Fig. 5 of the drawings to get a more clear understanding of the magnitude of the saw-tooth voltages induced in the rotating coils 21 and 22 of the rotating structure. In Fig. 5 has been illustrated graphically, time being plotted from left to right and potential being plotted vertically, by the graph 40 the saw-tooth energy generated by the saw-tooth generator STG. The solid lines of the second graph 41 illustrate the voltage induced in the coil 22 during one complete rotation of the rotor 21-22. It will be observed that at the extreme left of Fig. 5 the voltage graph 41 illustrates saw-tooth voltages of maximum value and that these values fall to zero when this rotor 21-22 has been rotated one-fourth turn, that they reach a maximum minus value when it has rotated a second quarter of a rotation, that this negative saw-tooth energy then again falls to zero upon completion of a third quarter of rotation and that it again rises to a maximum positive value at the completion of a whole revolution.

Referring now to the voltage graph 42 it will be observed that these saw-tooth voltages are zero when the voltage of graph 41 is maximum and

that in all other respects the curves 41 and 42 are alike. It may be pointed out that the beginning of the cycle illustrated for both graphs 41 and 42 correspond to the position of the apparatus as illustrated in Fig. 1A at which position the electron beam sweeps up from the point O on screen S.

Referring again to the solid lines of graph 42 it will be observed that this graph is exactly the same as the graph 41 (solid lines) except that the graph 42 lags 90° behind the graph 41.

It should now be remembered that commutators 25-26 and 27-28 have been provided and that the commutator 25-26, which commutes the saw-tooth energy for vertical sweeping, pole changes its leads when the voltage is zero as indicated by the arrows 45 and 46 in Fig. 5 of the drawings, whereas the commutator 27-28 commutes or pole changes the saw-tooth energy when this saw-tooth voltage is a maximum. The effect produced by this commutation by commutators 25-26 and 27-28 and illustrated by dotted lines in graphs 41 and 42, respectively (Fig. 5), results in different kinds of saw-tooth energy modulation. It will be noted that the graph 41 as modified by the dotted lines due to commutation includes only positive voltages and that these saw-tooth voltages rise and fall and are always pole changed when they are 0. The saw-tooth voltages for right and left sweep and illustrated by the graph 42 on the other hand start with a zero voltage, build up to a maximum positive voltage, then suddenly reverse to a maximum minus voltage which voltage is then gradually reduced to zero and then builds up in a positive direction until it returns to maximum positive value at which commutation takes place to pole change the leads to cause this maximum positive voltage to be suddenly changed into a maximum minus saw-tooth voltage, after which the minus voltages gradually reduce in value until they again reach the zero value upon completion of one revolution of shaft 23. This is as it should be in that if positive voltages are used to sweep the electron beam EB of the cathode-ray tube K toward the right of the center line of the screen S, it will be seen that as this screen is scanned toward the right and reaches its ultimate right-hand position the horizontal sweep should be suddenly reversed and the commutator 27-28 suddenly reverses this saw-tooth voltage and causes the next sweep to extend from the point O to the extreme left-hand lower part of the screen S. In other words, by looking at the screen S of the cathode-ray tube K the saw-tooth voltages sweep the electron beam toward the left and back to the point O successively in reduced value whereas the voltages which sweep vertically gradually increase so that the net result will be a diagonal sweep. That is, when the vertical voltage is a maximum the left-hand sweep voltage becomes 0 so that various slanting radial scan lines, like the spokes of a wheel, are produced on the screen as conventionally illustrated by dotted lines 47 to 53, inclusive, on the screen S.

In the normal position of the apparatus as shown in Fig. 1A the electron beam is scanned vertically upward very quickly and downwardly almost instantaneously along the line 50. As now the shaft 23 in Fig. 1 is turned in a counter-clockwise direction the voltages applied to the vertical plates 12 and 13 are gradually reduced and the voltages applied to the horizontal plates 10 and 11 are gradually increased in a positive direction so that various slanting lines of scan

conventionally illustrated by the dotted lines 51, 52 and 53 until the first quarter turn of rotation of the rotor 21-22 has been completed. At this point, end of first quarter turn, commutation takes place so that the voltage applied to horizontal plates 10 and 11, which is now a maximum, is suddenly reversed causing the electron beam to sweep to the left from the point O instead of sweeping to the right and so that the saw-tooth voltage applied to the sweep plates 12 and 13 again build up positively to cause the first half of a second sweeping of the screen S of the cathode-ray tube K to take place. In other words, the fluorescent screen S of the cathode-ray tube K is scanned radially twice during each revolution of the shaft 23. This shaft 23 is connected to the shaft 24 through the medium of reduction gears 145 and 146, whereas in the Figs. 2 and 3 constructions they are connected by one-to-one ratio gears 100 and 101, and in the Fig. 4 construction are connected through the medium of gears 147 and 148. In this connection it should be noted that the gears 145 and 146 cause the shaft 24 to rotate twice as fast as the shaft 23, the gears 147 and 148 of Fig. 4 cause the shaft 24 to rotate only half the speed of the shaft 23 and the shafts in each of Figs. 2, 3, 8 and 9 rotate at the same speed. The purpose for these various speed ratio gears and connections between shafts 23 and 24 will be more fully described hereinafter.

The apparatus shown in the lower portion of Fig. 1A of the drawings has been provided to activate the grid G of the electron gun of cathode-ray tube K at the proper instant out on the sweep and also on the proper radial line 48 to 53, inclusive, and others. The proper radial line on which a fluorescent dot is to be placed is selected by rendering the tetrode tube T inactive, through the medium of its suppression grid SG, during all other radial scans except the particular scan corresponding to the location in the field then under consideration, and this is done by supplying negative energy to this suppression grid SG of this tetrode T. The particular distance out on such radial line at which such fluorescent dot is placed is determined through the medium of the control grid CG of this tetrode T and depends on the distance the particular ground station is from the airplane. This tetrode includes the usual plate P, the usual cathode Ca, control grid CG, suppression grid SG, a plate battery BP and the usual plate transformer TrP.

The checking transformers TrC1 and TrC2 are employed to determine when the volume controlled voltages applied to the primary windings 60 and 61 of these respective transformers are in perfect phase and this is accomplished by having their secondary windings 62 and 63 connected in bucking relationship, as shown, to the amplifier-detector 65 through the mediums of wires 66 and 67. In other words, zero energy is only delivered from the transformers TrC1 and TrC2 to the amplifier 65 when the voltages applied to the primary windings 60 and 61 of these transformers are in exact phase. Out-of-phase energy so applied to these transformers and in turn to the amplifier-detector 65 is in turn converted into rectified potential of negative polarity and applied to the suppressing grid SG of the tetrode T, so that this tetrode T is at all times suppressed and the tube is at all times rendered inoperative so long as the voltages applied to the primary windings 60 and 61 are out of phase. It is of course assumed that the voltages applied

to these windings 60 and 61 are of the same value. In this connection it may be pointed out that the receivers R1 and R2 include suitable volume control apparatus so that their output voltages are substantially of identical magnitude.

If it is now desired to plot a fluorescent dot on the screen S at some other point when vertically above the point O and due to a field location which is not directly ahead of the airplane it is of course obvious that the radio energies received by the receivers R1 and R2 are then out of phase, for which reason no plotting will take place unless suitable means for phase shifting the radio current received from one of these receivers R1 or R2 is provided. It is therefore proposed to use phase shifting apparatus for shifting the phase of one of the received radio beams (the beam received from receiver R1) so as to artificially bring it into phase with the other radio beam at such time as the electron beam in the cathode-ray tube scans that area on the screen S corresponding to the actual area in the field where such ground station is located, and to apply these artificially synchronized energies to the primary windings of the transformers TrC1 and TrC2.

Such phase shifting apparatus has been provided through the medium of a rotary transformer including stationary coils 70 and 71, movable coil 72, and slip rings 73 and 74. The movable coil 72 and the slip rings 73 and 74 are supported by the shaft 24 heretofore described. When it is desired to shift phase to greater extents than 90 electrical degrees it is necessary to produce a rotating magnetic field, or a rotating electro-static field as for instance may be accomplished by apparatus such as shown in Fig. 7. For this reason the stationary coil 70 is provided with an inductance 71 to cause the current flowing therein to lag substantially 45° behind the impressed current and a condenser 72 is provided in the circuit of coil 71 to cause the current flowing in the coil 71 to lead the impressed voltage by substantially 45°. In other words, the current flow in the coils 70 and 71 is displaced substantially 90 electrical degrees so that a rotating magnetic field is produced about the center of these coils 70 and 71 as a result of which a voltage is induced in the movable coil 72 having a phase relationship with respect to the input voltage derived from the receiver R1 dependent upon the rotated position of this rotatable coil 72. The coils 70 and 71 receive their energy over wires 57 and 58 from receiver R1. The receiver R2 is connected to the primary winding 61 of transformer TrC2 through the medium of wires 68 and 69. The coil 72 is connected to the slip rings 73 and 74 through the medium of wires 75 and 76 and is in turn applied to the primary winding 60 of the transformer TrC1.

Since current flows in the coil 71 slightly earlier (1/4 cycle) than it flows in the coil 70 for a vertical field, the rotating magnetic field produced by these coils will rotate counterclockwise. Also, since rotation of the shaft 24 is clockwise the frequency applied to the input winding 60 of the transformer TrC1 is one cycle more than is the alternating current frequency applied to the primary winding 61 of the transformer TrC2 for each revolution of the shaft 24, so that if this shaft 24 rotates thirty-two revolutions per second, as would be true since the gear 145 is again as large as the pinion 146, the frequency of the energy applied to transformer TrC1 is

32 cycles per second more than the frequency of the current applied to the transformer TrC2. In other words, once during each revolution of the shaft 24 (twice for each revolution of the shaft 23) a complete cycle of phase shift takes place between the current supplied to the primary windings of transformers TrC1 and TrC2. Since the maximum phase shift that can exist between the currents received by receivers R1 and R2 is 360° it is readily seen that the phase shifting apparatus is back to its normal position after having modified one received current to all possible extents of out-of-phase condition that can exist, as a result of which a second phase shift cycle of compensation may be started immediately after an entire series of phase shift corrections have been completed.

In other words, as has been assumed and as would be the case, the radio currents received by receivers R1 and R2 are in perfect phase for all ground stations directly ahead of the airplane, and if the currents received by receiver R2 lags 180° behind that received by receiver R1 manifests that the station is to the left and at right angles to the center line of the airplane, but if it leads 180° it is a manifestation that the ground location is at right angles to the center line of the airplane and to the right thereof. To display these manifestations on the screen it will be necessary for the phase shifting apparatus illustrated in the lower part of Fig. 1A to subtract 180° of phase shift when the shaft 24 is in a position where the electron beam EB sweeps toward the left from the point O on screen S but is required to add 180° of phase shift to this current when the electron beam sweeps directly toward the right from the point O on the screen, corresponding but less pronounced phase shifts being made for intermediate points in the field and for intermediate radial lines on the fluorescent screen S of the cathode-ray tube K.

Operation—Fig. 1A.—Let us first assume that the apparatus is operating and that the saw-tooth modifier shown near the top of Fig. 1A and the phase shifter shown in the lower part of Fig. 1A are, during this operation, for at least a moment, assuming the position indicated in the drawing. Under this condition the saw-tooth voltage applied to the vertical sweep plates 12 and 13 is a maximum and the voltage applied to the horizontal sweep plates 10 and 11 of the cathode-ray tube K is zero as shown at arrow 83 (Fig. 5), so that sweeping of the electron beam EB over the dotted line 50 on screen S now takes place. At this time the airplane is pointing directly at the ground station Sta1 so that the ratio energies or space energies received therefrom by the receivers R1 and R2 are in perfect phase. Out-of-phase energies may be received from other ground stations at this time.

Since the coil 72 now assumes a position so as not to modify the phase of the energy transmitted from the receiver R1 to the primary winding 60 of the transformer TrC1 the phases of the currents in primary windings 60 and 61 remain in phase and the voltages induced in the secondary windings 62 and 63 are in perfect bucking relationship so that zero voltage is applied to the amplifier-detector 65 and to the suppressing grid SG of the tetrode T. No suppression of operation of this tetrode due to this reception is therefore now effective and the tube may be caused to function by the application of potential to its control grid. Also, at this time, and once for each sweep of the electron beam, voltage

is supplied over wires 68 and 78 to the control grid CG of this tetrode T. The tetrode T therefore functions at the proper instant and supplies high frequency energy to the grid G of the cathode-ray tube K to render the electron beam EB effective and plot the dot 44. This plotting of a fluorescent dot 44 on the line 50 of the cathode-ray tube K takes place at a point above the point O on the screen S a distance depending upon the distance the station Sta1 is from the airplane.

As the apparatus now continues to rotate, the electron beam EB sweeps back and forth over successive radial lines, such as line 51, on the screen S, and since it is assumed that there are no ground stations on the field corresponding to the area covered by the radial line 51 the phase corrections carried out by the phase shifting means shown in the lower part of Fig. 1 will not result in any reformed in-phase energies flowing in the primary windings 60 and 61 of the transformers TrC1 and TrC2 when this line 51 is being scanned, so that the suppressing grid SG of the tetrode T is continuously suppressing while the line 51 is being scanned by the electron beam. The amplifier-detector 65 is employed to produce a more or less continuous negative direct current suppressing voltage for the suppressing grid SG.

Let us now assume that the saw-tooth energy modifier shown in the top part of Fig. 1A and associated with shaft 23 has been rotated toward the left to an extent of substantially 45° to thereby cause scanning over radial line 52 on screen S. Under this condition medium saw-tooth voltages are applied to both sets of sweep plates 10-11 and 12-13 of the cathode-ray tube K in that this apparatus now assumes the position as indicated by arrow 80 in Fig. 5 of the drawings. The electron beam EB now sweeps over dotted line 52 illustrated on screen S. At this time radio energy picked up from station Sta2 reaches the receiver R2 substantially one-fourth cycle earlier than receiver R1. Since, however, the shaft 24 rotated a quarter of a revolution as compared with an eighth of a revolution of shaft 23 the voltage induced in rotatable coil 72 of the phase shifter has been advanced one-fourth of a cycle. In this connection it should be remembered that the direction of rotation of the magnetic field produced by stator coils 70 and 71 is counter-clockwise whereas the direction of rotation of shaft 24 and coil 72 is clockwise. In other words, the out-of-phase radio beams received by receivers R1 and R2 from station Sta2 are converted into in-phase energies which energies are applied to the primary windings 60 and 61 of the transformers TrC1 and TrC2 respectively so that the voltages induced in their secondary coils are in perfect bucking relationship in their circuit and zero suppressing energy is applied to the amplifier-detector 65 to allow the control grid CG to function and plot the fluorescent dot 64 on radial line 52.

The in-coming cycles, which are intermittent by reason of the impulse generator IG, cause momentary activation of the control grid CG to thereby plot a fluorescent dot 64 on the screen S, there being no suppression, at the proper distance out on the dotted line 52 to not only show in what direction the station Sta2 is located but to also manifest the distance to such station.

Let us now assume that the apparatus continues to rotate and when it has rotated to an extent where the saw-tooth modifier shown in the upper part of Fig. 1A has rotated 90° toward

the left and the phase shifter in the lower portion has rotated one-half revolution toward the right. Under this condition the saw-tooth energies will be of values as indicated adjacent the arrow 45 in Fig. 5 of the drawings, namely, the vertical plates will be energized by substantially zero saw-tooth voltage whereas the horizontal sweep plates will be energized by maximum voltage for sweeping the electron beam either toward the right or toward the left on the screen S depending upon whether pole changing by commutator 27-28 has taken place. It will be assumed that there is no field station toward the extreme right or left of the center line 81 of the airplane shown in Fig. 1B of the drawings, so that the energies applied to the primary windings 60 and 61 of the transformers TrC1 and TrC2 received from other stations are due to this phase shifting out of phase and causes suppression of functioning of the tetrode T.

Let us now assume that the apparatus continues to operate and the shaft 23 turns an additional 60° (60° change in radial scanning to radial dotted line 49) toward the left resulting in the turning of the shaft 24, 120° toward the right. Under this condition the saw-tooth voltages will be of a value as indicated by the arrow 82, so that the electron beam will sweep substantially over the radial dot line 49 on the screen S. Under this condition the radio energy received by receiver R1 from station Sta3 will lead the radio energy received by receiver R2 by substantially one-sixth cycle or substantially 60 electrical degrees.

This one-sixth cycle may be verified from Fig. 1B of the drawings for if the ground station Sta3 now under consideration is substantially 30° toward the left of the dotted line 81, 60° from the extreme left, as indicated by the dotted line 84, then the difference in the length of the lines 88 and 85, namely the distance from the point 86 to the receiving antenna RA2, is substantially proportional to this 30° angle. This is not strictly true, in that the line 86-RA2 is not a segment of the periphery of a circle drawn about antenna RA1 as a center but is substantially a cord. It should be noted that since line 84 is displaced 30° from line 81 and that line RA1-86 is displaced substantially 30° from the line RA1-RA2.

Since approximate correct plotting of stations on the screen S is all that is necessary it may for convenience be assumed that the line 86-RA2 is one-third the spacing of the receiving antennas RA1-RA2 so that the phase displacement of the currents is approximately 60°. In other words, the electron beam EB sweeps over the dotted line 49 of screen S at a time when the radio energy received by receiver R1 from a correspondingly located ground station Sta3 is artificially caused to lead by the phase shifter ahead of the radio energy received by receiver R2 by substantially 300° which is equivalent to a lag of 60°. That is, if the energy that is now picked up by antenna RA1 actually leads the energy picked up by antenna RA2 by 60° then this phase shifter which now creates an artificial lead of 300° (lag of 60°) will cause in-phase energies to be created and applied to the primary windings 60 and 61 of transformers TrC1-TrC2 to remove suppression and allow plotting of a fluorescent dot 54 on dotted line 49 of screen S. That is, the phase shifter assumes a position of clockwise rotation from the position illustrated in the drawings of 90°+90°+120° or 300°, which is five-sixths of a rotation of the rotor 12, so that the phase shifter of which it comprises a part will advance the

phase of the radio energy supplied to the primary winding 60 of the transformer TrC1 to an extent of substantially 300° the equivalent of retarding the phase 60° which is the electrical phase displacement between lines 49 and 50 (physical spacing is 30°). Since the energy supplied to receiver R1 from station Sta3 leads substantially 60° ahead of the energy received by receiver R2 from the same station this phase shifting function causes the energies supplied to the primary windings 60 and 61 of the transformers TrC1 and TrC2 to be in phase resulting in perfect bucking relationship of voltages in the circuit including secondary windings 62 and 63 and resulting in zero suppressing energy in the amplifier-detector 65 and resulting in zero suppressing energy being supplied to the grid SG of tetrode T. This tetrode T therefore is rendered responsive to energy applied to its control grid CG and when the radio energy applied at the beginning of a saw-tooth has been transmitted to station Sta3 and has returned back to the airplane the electron beam EB will have swept up on the line 49 a distance commensurate with the distance from the airplane to the station Sta3 and will plot a fluorescent dot at this point at line 49 as illustrated by dot 54.

Fig. 2 structure and operation.—This modified form of the invention, only partially illustrated in Fig. 2 of the drawings, is identical to the form illustrated in Fig. 1A in so many respects that only a small portion of the apparatus has been illustrated. In fact, the apparatus of this form of the invention, many parts of which have been omitted because they are identical, is identical to that shown in Fig. 1A, except in three respects. First, the radio frequency has been reduced to half, assuming the same spacing between antennas RA1 and RA2, so that these receiving antennas are spaced only one-fourth cycle apart instead of being spaced one-half cycle apart as was assumed in the Fig. 1A structure. All tuned units are, of course, correspondingly adjusted. Second, instead of employing slip rings 13 and 14 (Fig. 1A) for the phase shifter a single commutator including commutator segments 90 and 91 is employed, so that after phase shifting through 180° has been completed pole changing takes place and the same 180° portion of the cycle is then repeated. In other words, by the employment of the commutator 90-91 instead of modifying phase shift throughout the entire cycle only phase shifts for half-cycle compensations take place repeatedly, no phase shift correction for the other half-cycle being required because only a maximum of 90° lag or 90° lead in the currents received by receiver R1 with respect to the current received by receiver R2 can exist. In other words, the entire phase shift compensation which may be necessary for one scanning operation on the screen S is only a half-cycle and this takes place during a half revolution of the shaft 24 whereas in the Fig. 1A construction an entire revolution of the shaft 24 was necessary for making all the phase shift corrections that could be confronted during a single scan of the fluorescent screen S. Third, since the phase shift mechanism including the rotatable coil 72 of the Fig. 2 construction performs the entire phase shift modification during a single scan of the screen S, that is, during a half revolution, it is no longer necessary to operate the shaft 24 at twice the speed of the shaft 23 and these two shafts may operate at the same speed. For this reason instead of employing speed-up gears 145 and 146 (Fig. 1) one-to-one ratio gears 100 and 101 are employed.

In this connection reference should be had to Fig. 6 of the drawings to observe how phase shifting and the use of commutator 90—91 causes out-of-phase radio currents to be brought into phase when the electron beam EB of the cathode-ray tube scans the area on the screen S corresponding to the area in the field from which such out-of-phase radio currents radiate, for the Fig. 2 structure. When line 50 on screen S is scanned there is zero artificial phase shifting. This condition is effective at a point in the rotation of shaft 24 as indicated by arrows 160, 170 and 180 in Fig. 6. When scanning (left to right) on screen S has advanced somewhat beyond dotted line 53 almost 90° of artificial lead imposed on current from receiver R1 is necessary to bring current into phase and this is done and the condition is indicated by arrows 161, 163 and 165. An instant later, as shown by arrows 167, 168 and 169 (Fig. 6), commutation takes place.

Scanning now starts on the left half of the screen and just below dotted line 47. This condition is indicated by arrows 162, 164 and 166 on Fig. 6. One-fourth of a turn of shaft 24 after commutation has taken place (arrows 167, 168 and 169) zero artificial phase shift again takes place as indicated by arrows 160, 170 and 180 (Fig. 6). The phase shifter of Fig. 2 therefore makes two complete series of phase shift corrections during each revolution of shaft 24 for which reason no speed-up gearing is required and one-to-one ratio gears 100 and 101 are used. The graphs of Fig. 6 are exaggerated in certain respects in that many more cycles, than indicated, of radio frequency current pass between two successive commutations.

It is believed unnecessary to consider the operation of the modification illustrated in Fig. 2 in that it is the same as that of Fig. 1A except that since the maximum phase displacement that can exist between the radio currents received by receivers R1 and R2 is only a half-cycle (Fig. 2) instead of a whole cycle (Fig. 1A) the speed of the shaft 24 has been reduced in half and two complete phase shift correction functions are performed by this shaft 24 for each revolution thereof, whereas in the Fig. 1A structure a complete phase shift function requires a complete revolution of shaft 24. As already pointed out this is possible because the leads feeding the primary winding 60 of transformer TrC1 are pole changed each time a phase correction of 180° has been completed. In other words, the phase shift apparatus of Fig. 2 of the drawings can make only a maximum phase correction of 180° and it makes two such corrections during each revolution of the shaft 24.

Fig. 3 structure and operation.—Referring for a moment to Fig. 1A of the drawings it is obvious that the phase shifter shown therein advances the phase of the current supplied to the primary winding 60 one whole cycle during each revolution of the shaft 24. If now two such phase shifters were employed one of which advances the phase of the energy in the winding 60 over that received by the receiver R1 and a second phase shifter which retards the phase of the energy supplied to the primary winding 61 during each revolution of the shaft 24 then the rate of phase modification would be doubled and the speed ratio gears 145 and 146 of Fig. 1 would no longer be required in that a one-to-one gear ratio could be employed. This exact modification of Fig. 1A is illustrated in Fig. 3 of the drawings.

It will be seen that the gears 145 and 146 have been replaced by one-to-one ratio gears 100 and 101 and that a second phase shift structure including stationary coils 102 and 103 energized through a condenser 104 and an inductance 105 respectively are provided. It will be seen that this condenser 104 and inductance 105 are included in inverse order as compared with the inductance 71 and condenser 79 shown. This causes the rotating magnetic field set up by stationary coils 102 and 103 to rotate in the reverse direction as that produced by the coils 70 and 71 of Fig. 1 and also included in Fig. 3. It is thus readily seen that since the shaft 24 rotates in a clockwise direction that the alternating current induced in coil 72 will be increased by one cycle for each revolution of the shaft 24 whereas the alternating current induced in the rotatable coil 108 is reduced by one cycle for each revolution of the shaft 24, the net result is that for each revolution of the shaft 24 the current in the primary winding 60 of the transformer TrC1 passes the current supplied to the primary winding 61 of the transformer TrC2 twice and for this reason the shaft 24 need only run half as fast in the Fig. 3 structure as it would in the Fig. 1A structure. In Fig. 3 the energy derived from the rotating coil 72 is conducted to the primary winding 60 of the transformer TrC1 through slip rings 113 and 114 and wires 118 and 119 whereas the alternating current induced in the coil 102 is conducted to the primary winding 61 of the transformer TrC2 through the medium of slip rings 110 and 111 and wires 128 and 129. The operation of the system illustrated in Fig. 3 in all other respects is the same as that of the Fig. 1A structure so that detailed operation of this form of the invention is believed unnecessary.

Fig. 4 structure and operation.—Fig. 4 differs from Fig. 3 in exactly the same way as Fig. 2 differs from Fig. 1A. That is, in Fig. 4 the frequency chosen is such that the receiving antennas RA1 and RA2 are spaced one-fourth cycle apart (one-half in Fig. 3) so that the extent of phase shift which must be modified is limited to 180° or a half cycle. In order to avoid loss of time in having the phase shift apparatus operate through a half cycle where phase shifts are made by the structure that can never be used it is proposed to employ a commutator so that only phase shifts through an extreme range of 180° will be corrected. This has been accomplished by providing a four-segment commutator 112-115 of which the segments 112 and 114 are connected together to wire 116 and of which segments 113 and 115 are connected together and to the coil 72 through the medium of wire 117. The brushes engaging this commutator are connected through two suitable wires 118 and 119 to the leads of the primary winding 60 of the transformer TrC1. It is thus seen that after each one-fourth revolution of the shaft 24 pole changing of the input leads of the transformer TrC1 takes place so that since two cycles of correction are made through each revolution this pole changing takes place after each 180° of phase shift modification.

For reasons already pointed out the shaft 24 is then required to operate only one-half as fast as does the shaft 24 of Fig. 3, for which reason step-down gearing comprising a driving pinion 147 of half the diameter of the driven gear 148 has been provided so that the shaft 24 rotates half as fast as does the shaft 23. Stating this

in different words, since four complete phase shift corrections take place in each revolution of the shaft 24 and since two complete scanning operations are performed during each revolution of the shaft 23 the shaft 24 need only operate at half the speed of the shaft 23. It is believed unnecessary to discuss the operation of the modified form of the invention illustrated in Fig. 4 in that it functions exactly the same as does the form of invention illustrated in Fig. 3 except that maximum corrections of 180° are only required in the Fig. 4 structure whereas phase corrections extending through an entire cycle must be compensated for in the Fig. 3 structure. For this reason the speed of shaft 24 may be reduced in half from that of Fig. 1A by reason of the fact that two phase shifting rotary transformers are employed in Fig. 4 instead of only one as shown in Fig. 1A and may again be halved by reason of the commutation performed so that the speed of the shaft 24 in the Fig. 4 structure is only one-fourth that of the speed of the shaft 24 of the Fig. 1A structure.

Fig. 7 structure and operation.—The phase shift compensators illustrated, in Figs. 1A, 2, 3 and 4 are phase shifters of the rotary transformer or inductive type in which a rotating magnetic field is established with which a rotatable coil may come into inductive relationship at various points in its rotation.

Fig. 7 illustrates a phase shifter for accomplishing similar functions in which a rotating electro-static field is established through the medium of four condenser plates 121, 122, 123 and 124 which are fed by high potential secondary windings 126 and 127 of transformers Tr3 and Tr4. The voltages induced in the secondary windings 126 and 127 of these transformers are displaced in phase substantially 90° so that the condenser plates 121, 122, 123 and 124 become positive successively in that order once for each cycle. A rotatable condenser plate 130 is provided so as to electro-statically conduct current from these condenser plates 121-124 to the slip ring 131 successively in overlapped relation. Since the electro-static rotating field produced by the condenser plates 121-124 rotates counter-clockwise and since the shaft 24 rotates clockwise the energy delivered to the primary winding 60 of the transformer TrC1 is advanced one entire cycle over that of the current supplied to the primary windings of transformers Tr3 and Tr4 during each revolution of the shaft 24.

Since the phase shifting rate of the phase shifter illustrated in Fig. 7 is the same as that illustrated in Fig. 1A this electro-static phase shifter illustrated in Fig. 7 may be substituted for the inductive phase type shifter illustrated in Fig. 1A for obvious reasons. As pointed out hereinafter the voltages induced in the secondary windings 126 and 127 of the transformers Tr3 and Tr4 are displaced 90° in phase. It may be pointed out that this phase displacement is accomplished through the medium of the condenser 134 and the resistance 135 connected across the primary windings 136 and 137 of the transformers Tr3 and Tr4 respectively.

It may be pointed out that these primary windings 136 and 137 are connected in series and that the current flowing in the winding 137 leads the current flowing in the winding 136 because the winding 136 is shunted by a condenser 134 and the winding 137 is shunted by a resistance 135. This condenser 134 is of such capacity and resistance 135 is of such ohmic value that the phase

displacement in the primary windings 136 and 137 is substantially 90 electrical degrees.

Since the functioning of the system is exactly the same irrespective of whether inductive type phase shifters or electro-static type phase shifters are employed no description of the operation of the system when such electro-static phase shifters are employed is believed necessary and will therefore not be given. The one-to-one ratio gears illustrated in Figs. 2 and 3 will in practice be preferably omitted and a shaft coupling used instead. These gears have been illustrated to avoid confusion relative to direction of rotation of the phase shifters.

Fig. 8 structure and operation.—In each of the forms of invention illustrated in Figs. 1, 2, 3 and 4 phase shifting of radio frequency currents was accomplished by electro-magnetic inductive phase shifting means whereas in the form illustrated in Fig. 7 this was accomplished by a rotatable phase shifter of the capacitance type. There is still another principle whereby phase shifting to bring out-of-phase radio currents into phase and that is by varying the length of the conducting path of the received radio current. If the length of the path were to be varied by changing the length of a conductor over which the current must flow the apparatus would become unduly cumbersome in view of the tremendous speed of electric wave motion in a metallic conductor, and for this reason this method of changing the lengths of the conducting path is impracticable. The speed of movement of the incoming radio energy is, however, tremendously reduced where this energy exists in the form of flow of electrons in space in an electron tube.

Speaking generally, the velocity of an electron in an amplifier may be as low as $1/1000$ of the velocity of the radio wave in space which caused the electron flow. It is therefore proposed to provide means whereby each of the two received radio energies flow through variable length cathode-to-anode distances in an amplifier tube. In order to create such variable distances from cathode-to-anode it is proposed to cause the electron flow in the tube to be concentrated into a rather narrow beam and to provide means for rotating this beam about a cathode eccentrically located with respect to the axis of a semi-cylindrical plate or anode.

A structure of this type has been illustrated in Fig. 8 wherein there have been illustrated two selector type amplifying tubes ST1 and ST2. Each of these tubes comprises a cylindrical envelope or glass tube in which there are concentrically provided two semi-circular plates or anodes PS1 and PS2. Eccentrically enclosed with respect to the center of the envelope ES and similarly eccentrically located with respect to the axis of two plates PS1 and PS2 there is provided a cylindrical cathode CS about which there is concentrically located a grid GS. The cathode CS is heated in the usual way as by a filament passing through the center thereof and the grid GS is of the usual screen construction. If potential is supplied between the plate PS1 and the cathode CS and this cathode CS is heated electrons will flow from the cathode CS to the plate with more or less uniform distribution. If, however, the grid GS is biased negatively this electron flow will be reduced and if it is biased positively the electron flow from the cathode CS will increase.

It is well understood that if an electron is projected through a path cutting the lines of a mag-

netic field that this electron flow will be in a spiral trajectory or path the curvature of which depends upon its velocity and the strength of the magnetic field. If, however, such electron is projected, through a magnetic field in a direction parallel to the lines of magnetic flux there is no such curving of the electron path. In view of this phenomenon it is proposed to provide a strong magnetic field through the envelope ES in a direction at right angles to the axis of this envelope and to cause this magnetic field to rotate about the axis of the cathode at a speed equal to or proportional to the speed of the shaft 23. This shaft 23 is used for scanning the electron beam in the cathode-ray tube K in the same manner as in Fig. 1A.

In order to produce a rotating magnetic field a typical two-phase motor stator, preferably of the toothed type is provided, in the slots of which there is wound a two-pole two-phase winding DW of the usual distributed type construction so that if this winding is energized by two-phase alternating current the desired rotating magnetic field will be present. Three-phase or six-phase windings and corresponding sources of energy may of course be used. This cylindrical stator and distributed winding has been conventionally shown and has been designated DW. Since the selector tubes ST1 and ST2 are identical like parts have been assigned like reference characters. As shown the distributed windings DW are energized by two-phase alternating current from a two-phase alternating current generator 2PG. As shown in Fig. 8 the anode PS2 in each of the tubes ST1 and ST2 is not used and is merely provided to assist in carrying off the electrons which are projected toward this anode. This anode is preferably connected to the cathode CS through a suitable discharge resistance (not shown).

The two anodes PS1 are supplied with current of positive polarity from the plate battery BP1, the selector tube ST1 having included in its plate circuit the primary winding 60 of the transformer TrC1 whereas the selector tube ST2 has included in its plate circuit the primary winding 61 of the transformer TrC2. These transformers are part of the systems heretofore described. Also, the grid GS of the tube ST1 is connected to and at times activated by radio frequency current delivered by the receiver R1 whereas the grid GS of the other tube ST2 is connected to and at times activated by energy delivered by the receiver R2.

When the electron beams Eb cooperating with the anode PS1 assumes the position illustrated in Fig. 8 the energy supplied from the receiver R1 must flow over a much greater distance within the tube ST1 than does the energy supplied from the receiver R2 within the tube ST2. In other words, the transmitting distance through the tube ST1 is greater than average whereas the transmitting distance in the tube ST2 for this position of the electron beam is shorter than average, so that the current in the plate circuit of the selector tube ST1 has been caused to lag whereas the plate current flowing in the plate circuit of the selector tube ST2 has been caused to lead with respect to average. When, however, the shaft 23 assumes a position where the screen S of the cathode-ray tube K is being scanned vertically upwardly then the phases of the currents delivered by the two-phase generator 2PG are such as to cause polarity of the rotating magnetic field to be positioned and the electron beam Eb of the tube ST1 to assume the position 150 and the electron beam Eb of the tube ST2 to assume

the position 151. It will be observed that the distances from the cathode CS to the plate PS1 over paths 150 and 151 in tubes ST1 and ST2 respectively are of equal length so that the currents passing therethrough have not been caused to either lead or lag in that such delay as was caused by both must be considered the normal and average condition. From this consideration it is readily seen that if the antennas RA1 and RA2 are spaced one-half wave length apart so that the greatest displacement in phase that can ever exist is one whole cycle or 360° and that if the electron speed in these tubes is such that the difference between the longest and shortest electron beam Eb is one-half wave length that a whole wave length of shift in phase will be produced by each half revolution of the electron beam Eb. Since the shaft 23 causes the fluorescent screen S to be scanned twice in each revolution it is immediately apparent that no gear ratio between shaft 23 and shaft 24 is necessary and for this reason the shafts 23 and 24 have been illustrated coupled together by a coupling 154.

Since the selector tubes ST1 and ST2 are to be used to amplify alternating current very little or no grid bias is preferably applied to the grids GS so that the application of alternating current to these grids GS will result in sine wave fluctuations of the plate currents passing through the primary windings 60 and 61 of transformers TrC1 and TrC2 so that strictly alternating currents flow in the secondary windings 62 and 63 respectively of these transformers.

Obviously the structure and operation of the system beyond the transformers TrC1 and TrC2 is the same as that of the Fig. 1 construction for which reason it is deemed unnecessary to discuss the operation of the system any further.

Fig. 9 structure and operation.—Since the apparatus illustrated in Fig. 8, and just described, not only lends itself to produce phase shift in alternating currents but also lends itself to the measurement of difference of the time of arrival of two different pulses of radio energy the invention may take still a slightly different form and this has been illustrated in Fig. 9 of the drawings.

In the form of the invention, as illustrated in Fig. 9, the radio receivers R1 and R2 have been shown replaced by radio receivers and detectors RD1 and RD2, these receiver-detectors deliver rectified current instead of the alternating current from space radiation received through the medium of their associated receiving antennas RA1 and RA2. In other words, direct current pulses are dealt with beyond the receiver-detector units RD1 and RD2. Since the two selector tubes ST1 and ST2 are identical to the selector tubes illustrated in Fig. 8 these selector tubes as well as all of their component parts have been designated by like reference characters. From a complete understanding of the apparatus disclosed in Figs. 1A and 1B of the drawings and the operation of this Fig. 1A apparatus and from the fact that the receivers R1 and R2 have been replaced by receiver-detectors RD1 and RD2 in Fig. 9, it is obvious that the potentials applied to the grids GS of the tubes ST1 and ST2 of Fig. 9 will at times arrive simultaneously and will at other times arrive in sequence, depending upon whether the ground station ahead of the airplane is straight ahead or is to one side or the other of the center line of the airplane. It will also be understood that the control grid CG of the tube T will be energized by a positive pulse over wire 78

each time that a reflected radio pulse reaches the airplane carried antenna RA2. In order to at times prevent these pulses from being effective and at other times allow them to cause the flow of current in the plate circuit of this tube T the suppression grid SG of this tube T is connected to the secondary windings 62 and 63 of the transformers TrC1 and TrC2. This circuit includes the secondary windings 62 and 63 in bucking relationship, and a condenser 156 which is shunted by a high resistance unit 157. This condenser 156 and resistance unit 157 have been provided to maintain or hold over the momentary pulse that will be created through the medium of the circuit including secondary windings 62 and 63 due to out-of-phase current supplied to the grids GS. The structure is such as to cause the pulse to be maintained at least as long as the received radio pulse lasts. In this connection it is proposed that the control grid CG of the tetrode T will be maintained active during the entire pulse of radio energy whereas the secondary windings 62 and 63 in series will deliver a voltage only during the non-overlapped portion of the two received rectified radio pulses and this hold-over, effected by the condenser 156 and resistance unit 157, will cause the suppression grid SG to suppress received impulses that are non-synchronous and this suppression will continue throughout the entire overlapped portion of the received impulses, whereas if two impulses are simultaneously received (overlapping from the start) no net voltage will be delivered by the secondary windings 62 and 63 of transformers TrC1 and TrC2 in series so that no suppression of actuation of the tetrode T will take place.

The operation of this modified form of the invention beyond the tetrode T is exactly the same as that illustrated in Fig. 3, the coupling 154 having been provided in place of the one-to-one gear ratio illustrated in Fig. 3 of the drawings, for which reason a detailed discussion of the operation of the form of invention illustrated in Fig. 9 is believed unnecessary and will be dispensed with.

The applicants have thus shown and described numerous forms of their invention. Insofar as Figs. 1-4 are concerned this has been done to get a more clear understanding of the principles underlying the invention rather than to show different species thereof. Figs. 7, 8 and 9 illustrate other forms of the invention employing generally the same principle of operation. In all the forms of the invention illustrated radial scanning of the fluorescent screen has been disclosed specifically but it should be understood that slow horizontal and fast vertical scanning such as disclosed in our prior application, Ser. No. 558,256, filed October 11, 1944, may be used, if desired. Other changes, modifications and adaptations of the invention may be made within the spirit and scope of the invention and so long as these changes come within the scope of the following claims.

What we claim as new is:

1. In a system of the type described; the combination with an airplane carried cathode-ray tube including an electron gun, a fluorescent screen and means for causing an electron stream emitted by said gun to scan said screen in a predetermined manner; a radio transmitting antenna on the ground and two radio receiving antennas on said airplane, said receiving antennas being located along a line substantially parallel to the transverse axis of the airplane

and being separated a predetermined distance; and means for causing said electron gun to be activated for predetermined phase displacements between radio currents received from said transmitting antenna simultaneously by said receiving antennas depending on the part of said screen which is then being scanned by said electron stream.

2. In a system of the type described; the combination with an airplane carried cathode-ray tube including an electron gun, a fluorescent screen and means for causing an electron stream emitted by said gun to scan said screen back and forth over successive radial lines emanating from a predetermined point on the screen; a radio transmitting antenna on the ground and two radio receiving antennas on said airplane, said receiving antennas being located along a line substantially parallel to the transverse axis of the airplane and being separated a predetermined distance; and means for causing said electron gun to be activated for predetermined phase displacements between radio currents simultaneously received from said radio transmitting antenna by said receiving antennas depending on the radial line on said screen which is then being scanned by said electron stream.

3. In a system of the type described; the combination with an airplane carried cathode-ray tube including an electron gun, a fluorescent screen and means for causing an electron stream emitted by said gun to scan said screen in a predetermined manner; a radio transmitting antenna on the ground and two radio receiving antennas on said airplane, said receiving antennas being located along a line substantially parallel to the transverse axis of the airplane and being separated a predetermined distance; and means including phase shifting apparatus for causing said electron gun to be activated for predetermined phase displacements between radio currents simultaneously received by said receiving antennas from said transmitting antenna depending on the part of said screen which is then being scanned by said electron stream.

4. In a radio route delineating system for guiding pilots on airplanes; the combination with a transmitting antenna and two receiving antennas carried by an airplane, said receiving antennas being located along a line substantially parallel to the transverse axis of the airplane and a predetermined distance apart; a ground located radio re-radiating station which when activated by radio energy of a particular frequency radiates radio energy of the same frequency, whereby if such re-radiated energy reaches the airplane from which it was transmitted from any other point than straight ahead phase displaced radio energy is received in said two receiving antennas; a cathode-ray tube on said airplane including an electron gun, a fluorescent screen and scanning means for sweeping an electron stream emitted by said gun to scan said screen in a predetermined manner; an electronic tube including a control grid and a suppressing grid; suppressing means for rendering said suppressing grid active to thereby render said electronic tube inactive when out of phase radio energies are received by the respective receiving antennas; phase shifting means effective when rendering active to modify the phase of the radio energy received by one of said receiving antennas to match the phase of radio energy received by the other receiving antennas; means for rendering said control grid active each time radio en-

ergy is received by one of said receiving antennas; and means governed by said scanning means effective to render said phase shifting means active and thereby permit said electronic tube to be active whenever the fluorescent screen in said cathode-ray tube is being scanned by its electron stream in an area on said screen corresponding to the location of the ground located re-radiating station from which such radio energies were transmitted.

5. In a radio route delineating system for guiding pilots on airplanes; the combination with a transmitting antenna and two receiving antennas carried by an airplane, said receiving antennas being located along a line substantially parallel to the transverse axis of the airplane and a predetermined distance apart; a ground located radio re-radiating station which when activated by radio energy of a particular frequency radiates radio energy of the same frequency, whereby if re-radiated energy which originates at such transmitting antenna reaches the receiving antennas on said airplane from any re-radiating station other than a station straight ahead phase displaced radio energies are received in said two receiving antennas; a cathode-ray tube on said airplane including an electron gun, a fluorescent screen and means for sweeping an electron stream emitted by said gun to scan said screen radially with respect to a point on said screen; an electronic tube effective when active to increase the intensity of said electron stream, said electronic tube including a control grid and a suppressing grid; suppressing means for rendering said suppressing grid active to thereby render said electronic tube inactive when radio energies are received which are not in phase; phase shifting means for modifying the phase of the radio energy received by one of said receiving antennas; means for rendering said control grid active each time radio energy is received by one of said receiving antennas; and means governed by said scanning means effective to render said phase shifting means active and thereby permit said electronic tube to be active whenever the fluorescent screen in said cathode-ray tube is being scanned by its electron stream over a radial line on said screen corresponding to the location of the ground located re-radiating station which emitted such radio energies.

6. In a radio route delineating system for guiding pilots on airplanes; the combination with a transmitting antenna and two receiving antennas carried by an airplane, said receiving antennas being located along a line substantially parallel to the transverse axis of the airplane and a predetermined distance apart; a ground located radio re-radiating station which when activated by radio energy of a particular frequency will radiate radio energy of a given frequency, whereby if such re-radiated energy reaches the airplane from which it was transmitted from any other point than straight ahead the two detected radio energies will be received in said two receiving antennas successively; a cathode-ray tube on said airplane including an electron gun, a fluorescent screen and means for sweeping an electron stream emitted by said gun to scan said screen in a predetermined manner; an electronic tube for governing the intensity of said electron stream, said electronic tube including a control grid and a suppressing grid; suppressing means for rendering said suppressing grid active to thereby render said electronic tube

inactive when only one of said two receiving antennas are activated at a time; modifying means for causing successively arrived radio energies received by said receiving antennas to be brought into synchronism; means for rendering said control grid active each time radio energy is received by one of said receiving antennas; and means for coordinating said modifying means and said scanning means so that in-synchronism radio energies created by said modifying means are only supplied to result in inaction of said suppressing means while rendering said control grid active when the fluorescent screen in said cathode-ray tube is being scanned by its electron stream in an area on said screen corresponding to the location of the ground located re-radiating station which emitted such radio energies.

7. A route delineating system for blind flying comprising; an airplane carried cathode-ray tube including a fluorescent screen, an electron gun and means for causing said fluorescent screen to be scanned by an electron stream emitted from said gun over radial lines all starting at a common point each scan moving out very quickly and returning almost instantly, a plurality of ground stations defining air routes, means for emitting a train of radio waves toward said ground stations at the beginning of each radial line scan, means at each ground station for returning a corresponding train of waves back to the airplane, receiving means on the airplane including spaced antennas for comparing the phase of radio frequency waves received simultaneously by the respective antennas from each of the ground stations, and means on said airplane responsive to said receiving means for plotting a fluorescent dot on a particular radial line by rendering said electron stream active only if there is an active ground station located in a corresponding radial direction ahead of the airplane.

8. A route delineating system for blind flying comprising; an airplane carried cathode-ray tube including a fluorescent screen, an electron gun and means for causing said fluorescent screen to be scanned by an electron stream emitted from said gun over radial lines all starting at a common point each scan moving out very quickly and returning almost instantly, a plurality of ground stations defining air routes, means for emitting a train of radio waves toward said ground stations at the beginning of each radial line scan, means at each ground station for returning a corresponding train of waves back to the airplane, receiving means on the airplane including spaced antennas for comparing the phase of radio frequency waves received simultaneously by the respective antennas from each of the ground stations, and means on said airplane responsive to said receiving means for plotting a fluorescent dot on a particular radial line by rendering said electron stream active only if there is an active ground station located in a corresponding radial direction ahead of the airplane and plotting such dot on said radial line at a distance out from said common point commensurate with the distance from such airplane to such ground station.

9. In a system of the type described; the combination with an airplane carried cathode-ray tube including an electron gun, a fluorescent screen and means for causing an electron stream emitted by said gun to scan said screen in a predetermined manner; a radio transmitting antenna on the ground and two radio receiving antennas on said airplane, said receiving antennas being located along a line substantially parallel

to the transverse axis of the airplane and being separated a predetermined distance; and means including phase shifting means for selectively advancing or retarding the phase of the radio energy received by one of said receiving antennas in accordance with whether said transmitting antenna on the ground is to the left or right of the longitudinal axis of the airplane for causing said electron gun to be activated for predetermined phase displacements between radio energies received by said receiving antennas depending on the part of said screen which is then being scanned by said electron gun.

10. A route delineating system for blind flying comprising; an airplane carried cathode-ray tube including a fluorescent screen, an electron gun and means for causing said fluorescent screen to be scanned by an electron stream emitted from said gun over radial lines all starting at a common point each scan moving out very quickly and returning almost instantly, a plurality of ground stations defining air routes, means on the airplane for emitting a train of radio waves toward said ground stations at the beginning of each radial line scan, means at each ground station for returning a corresponding train of waves back to the airplane, receiving means on the airplane including spaced antennas for comparing the phase of radio frequency waves received simultaneously by the respective antennas from each of the ground stations and means on said airplane responsive to said receiving means for plotting a fluorescent dot on a particular radial line by rendering said electron stream active only if there is an active ground station located in a
